(57) **CLAIM**

The ornamental design for a pet treat, as shown and described herein.

DESCRIPTION

FIG. 1 is a perspective view of an embodiment of the present invention.

FIG. 2 is a front view of the embodiment of the invention of FIG. 1.

FIG. 3 is a back view of the embodiment of the invention of FIG. 1.

FIG. 4 is a left view of the embodiment of the invention of FIG. 1.

FIG. 5 is a right view of the embodiment of the invention of FIG. 1.

FIG. 6 is a top view of the embodiment of the invention of FIG. 1; and,

FIG. 7 is a bottom view of the embodiment of the invention of FIG. 1.

1 Claim, 3 Drawing Sheets

FIG. 2

FIG. 3

FIG. 1

FIG. 4

FIG. 5

FIG. 6

FIG. 7
